JAMES A. KEYES, OF NEW YORK, N. Y.

LOCKING DEVICE.

1,112,915.

Specification of Letters Patent.

Patented Oct. 6, 1914.

Application filed March 16, 1912. Serial No. 684,098.

To all whom it may concern:

Be it known that I, JAMES A. KEYES, a citizen of the United States, and resident of the city, county, and State of New York, have invented certain new and useful Improvements in Locking Devices, of which the following is a specification.

This invention relates to a locking device adapted for use in connection with any mechanism in which it is desired to control or lock the same against movement.

The object of the invention is to provide a device for the purpose set out which may be operated to lock when the parts are in a given position and which also operates to permit a movement of the parts toward or in the direction of the locked position while preventing movement away from this position.

20 In carrying out the invention in the form shown in the drawings a shaft is provided which is connected to the mechanism to be controlled or locked. Upon this shaft are mounted a locking member or disk and a 25 ratchet member which are arranged to be engaged by a locking bolt and a pawl respectively when the device is operated, all of which will be explained more fully hereinafter in connection with the description 30 of the embodiments of the invention as illustrated.

In the drawings like parts in the several views have been given the same reference numerals.

35 Figure 1 is a front elevation of a locking device embodying the invention. Fig. 2 is a sectional side view, taken on the line 2—2 of Fig. 1.

40 A base 1 is provided with a suitable bearing for the support of the shaft 2, to which is attached an arm 3 which is connected with the mechanism to be controlled or locked by the device.

45 A locking disk 4, a cam 5 and a ratchet disk 6 are secured to the shaft 2 by means of the lock nut 7, which is arranged to hold these members against a shoulder on the shaft so that the same rotate therewith and at the same time provide means for adjusting the relative position of the several members, the purpose of which will be explained more fully hereinafter.

55 The locking disk 4 is provided with a notch or recess 8 in the periphery thereof and a slidable member 9 is positioned so that one end enters the notch 8 when the

disk 4 is in a predetermined position and thus holds or locks the same against movement in either direction.

The sliding member or locking bolt 9 is 60 slidably mounted in a suitable support or bearing 10 upon the base 1 and is moved into and out of the notch 8 by means of the operating lever 11. This operating lever 11 is normally held in the position shown in 65 Fig. 1 by means of the spring 12, in which position the locking bolt 9 is inoperative. An extending arm from the operating lever 11 carries an armature 13 which is operated upon by the electromagnet coil 14 for moving the operating lever 11 and the locking bolt 9 into its operative position when current flows through the coil 14, as will be readily understood by reference to Fig. 1 of the drawings. A terminal block 15 may 70 be mounted upon the base 1 to provide for the electrical connections for the current supply to the coil 14.

A pin 16 in the locking bolt 9 is so positioned as to engage a double pawl 17, which 80 is pivotally mounted upon the support 10. This pin 16 when in the position shown in Fig. 1 acts as a stop for holding the pawl 17 out of engagement with the ratchet teeth on the ratchet disk 6.

A latch 18 is held by means of a spring 19 with one end in engagement with the pawl 17, the opposite end of the latch 18 being pivotally mounted at one end of a cam operated lever 20, which is held by 90 means of the spring 21 with its opposite end in engagement with the cam 5.

One of the uses for which this device is adapted is in connection with the operating mechanism of an elevator. When used in 95 this connection the arm 3 is connected to the starting or controlling mechanism of the elevator car and may be arranged to lock the controlling mechanism under certain conditions in its stop position. The normal stop 100 position of the locking device with relation to the stop position of the controlling mechanism is not the same at all times but varies somewhat due to the stretching of the cables and other causes so that it becomes important in this connection to provide for locking the controlling mechanism to prevent its movement or operation away from its normal stop position. In this case the normal stop position would be with the notch 8 opposite the end of the locking bolt 9 so that 110 when the circuit is closed through the mag-

net coil 14 the armature 13 will be attracted and the operating lever 9 caused to move the locking bolt into the notch in the locking disk 4 in which position the operating mechanism will be held or locked as long as the current flows through the magnet coil 14. Assuming, however, that the operating mechanism does not stand exactly in the normal stop position but slightly to one side thereof 10 when the circuit is closed through the magnet coil 14, the upper end of the locking bolt 9 will rest upon the periphery of the locking disk 4. The movement of the locking bolt 9 carries the pin 16 out of engagement with 15 the pawl 17 and permits the left end of the same to move from its position as shown in Fig. 1 and to engage the ratchet teeth on the periphery of the ratchet disk 6, the pawl being operated by the latch 18 which engages 20 one of the inclined sides thereof, as shown in Fig. 1. When the parts are in this position it will be seen that the pawl 17 will prevent the shaft 2 from being rotated in a counter-clockwise direction but will permit 25 movement in a clockwise direction, consequently, it is only possible for the operator to move the operating mechanism toward the normal or stop position and as soon as it has reached this position the locking bolt 9 will 30 enter the notch 8 and lock the mechanism against movement in either direction, as explained above.

Should the operating mechanism have been moved to the other side of its normal stop 35 position the cam 5 will have been rotated, causing the inclined portion 22 of the cam face to move the upper end of the cam lever 20 to the right and its lower end carrying the latch 18 to the left. This movement 40 causes the end of the latch 18 to pass over the extreme lower edge of the pawl 17 to the oppositely inclined face thereof, setting the pawl 17 in position to be operated to engage the oppositely inclined ratchet teeth of the 45 ratchet disk 6 in a manner like that just described for its operation on the other side.

A further object of the pin 16 which is carried by the locking bolt 9 is to engage the pawl 17 when the circuit is opened through 50 the magnet coil 14, which permits the operating lever 11 and locking bolt 9 to be moved downwardly by the spring 12 to their inoperative position. It will thus be seen that with this arrangement the device may be 55 operated not only to lock in a certain position but to automatically prevent any movement of the mechanism in either direction away from this locking position regardless of which side of this position the mechanism 60 stands when the device is operated.

As many changes could be made in the above construction and many apparently widely different embodiments of my invention designed without departing from the 35 scope of the appended claims, I intend that

all matter contained in the above description or shown in the accompanying drawings shall be interpreted as illustrative merely of an operative embodiment of my invention and not in a limiting sense.

What I claim is:

1. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, means for setting said pawl in position to engage one of said sets of ratchet teeth, means for holding said pawl in an inoperative position, and means for operating said locking bolt and releasing said pawl.

2. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, means for setting said pawl in position to engage one of said sets of ratchet teeth, means controlled by said locking bolt 90 for holding said pawl in an inoperative position, and means for operating said locking bolt and releasing said pawl.

3. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, means for setting said pawl in position to engage one of said sets of ratchet teeth, means for holding said pawl in an inoperative position and for restoring 110 the same to said position, and means for operating said locking bolt and releasing or restoring said pawl in position to engage said ratchet teeth.

4. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, means for setting said pawl in position to engage one of said sets of ratchet teeth, a cam operatively connected 125 with said locking member and ratchet member and adapted to operate said means, means for holding said pawl in an inoperative position, and means for operating said locking bolt and releasing said pawl.

5. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, means for setting said pawl in 5 position to engage one of said sets of ratchet teeth, a cam operatively and adjustably connected with said locking member and ratchet member and adapted to operate said means, means for holding said pawl in an inoperative position, and means for operating said locking bolt and releasing said pawl.

6. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, means for setting said pawl in position to engage one of said sets of ratchet teeth, a cam operatively connected with said locking member and ratchet member and adapted to operate said means, means permitting the adjustment of the relative position of said locking member ratchet member and cam, means for holding said pawl in an inoperative position, and means for operating said locking bolt and releasing said 35 pawl.

7. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, a cam operatively connected with 40 said locking member and ratchet member and adapted to operate a lever engaged thereby, a lever adapted to be operated by said cam, means carried by said lever for setting said pawl in position to engage one of said sets of ratchet teeth, means for holding said pawl in an inoperative position, and means for operating said locking bolt and releasing said pawl.

8. In a locking device, in combination, a 55 movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, a cam operatively connected with said locking member and ratchet member and adapted to operate a lever engaged thereby, a lever operated by said cam, a spring pressed latch

carried by said lever engaging said pawl and adapted to move the same in position to engage one of said sets of ratchet teeth, means for holding said pawl in an inoperative position, and means for operating said locking bolt and releasing said pawl.

9. In a locking device, in combination, a movable locking member, a locking bolt adapted to lock said member against movement in either direction, a movable ratchet member having two sets of teeth inclined in opposite directions, a pawl adapted to engage either of said sets of teeth and prevent movement of said ratchet member in one direction, means for setting said pawl in position to engage one of said sets of ratchet teeth, said pawl also having oppositely inclined faces adapted to be engaged by said means, a cam operatively connected with said locking member and ratchet member, a lever engaged and adapted to be operated by said cam, means for holding said pawl in an inoperative position, and means for operating said locking bolt and releasing said pawl.

10. In a locking device, in combination, a rotatable locking disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, means for setting said pawl in position to engage one of said sets of ratchet teeth, means for holding said pawl in an inoperative position, and means for operating said locking bolt and releasing said pawl.

11. In a locking device, in combination, a rotatable locking disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, means for setting said pawl in position to engage one of said sets of ratchet teeth, means controlled by said locking bolt for holding said pawl in an inoperative position, and means for operating said locking bolt and releasing said pawl.

12. In a locking device, in combination, a rotatable locking disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, means for setting said pawl in position to engage one of said sets of ratchet teeth, means for holding said pawl in an inoperative position and for restoring the same to said position, and means for operating said 130

locking bolt and releasing or restoring said pawl in position to engage said ratchet teeth.

13. In a locking device, in combination, a rotatable locking disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, means for setting said pawl in position to engage one of said sets of ratchet teeth, a cam operatively connected with said locking disk and ratchet disk and adapted to operate said means, means for holding said pawl in an inoperative position, and means for operating said locking bolt and releasing said pawl.

14. In a locking device, in combination, a rotatable locking disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, means for setting said pawl in position to engage one of said sets of ratchet teeth, a cam operatively and adjustably connected with said locking disk and ratchet disk and adapted to operate said means, means for holding said pawl in an inoperative position, and means for operating said locking bolt and releasing said pawl.

15. In a locking device, in combination, a rotatable disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, means for setting said pawl in position to engage one of said sets of ratchet teeth, a cam operatively connected with said locking disk and ratchet disk and adapted to operate said means, means permitting the adjustment of the relative position of said locking disk, ratchet disk and cam, means for holding said pawl in an inoperative position, and means for operating said locking bolt and releasing said pawl.

16. In a locking device, in combination, a rotatable locking disk, a locking bolt adapted to lock said disk against movement in either direction, a rotatable ratchet disk

having two sets of teeth inclined in opposite directions, a pawl adapted to engage either of said sets of teeth and prevent rotation of said ratchet disk in one direction, a cam operatively connected with said locking disk and ratchet disk and adapted to operate a lever engaged thereby, a lever operated by said cam, means carried by said lever for setting said pawl in position to engage one of said sets of ratchet teeth, means for holding said pawl in an inoperative position, and means for operating said locking bolt and releasing said pawl.

17. In a locking device, in combination, a rotatable locking disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, a cam operatively connected with said locking disk and ratchet disk and adapted to operate a lever engaged thereby, a lever operated by said cam, a spring pressed latch carried by said lever engaging said pawl and adapted to move the same in position to engage one of said sets of ratchet teeth, means for holding said pawl in an inoperative position, and means for operating said locking bolt and releasing said pawl.

18. In a locking device, in combination, a rotatable locking disk, a locking bolt adapted to lock said disk against movement in either direction, a rotatable ratchet disk having two sets of teeth inclined in opposite directions, a pawl adapted to engage either of said sets of teeth and prevent rotation of said ratchet disk in one direction, means for setting said pawl in position to engage one of said sets of ratchet teeth, said pawl also having oppositely inclined faces adapted to be engaged by said means, a cam operatively connected with said locking disk and ratchet disk, a lever engaged and adapted to be operated by said cam, means for holding said pawl in an inoperative position, and means for operating said locking bolt and releasing said pawl.

Signed at New York city, N. Y., in the county and State of New York, this 7th day of march, 1912.

JAMES A. KEYES.
